UNITED STATES PATENT OFFICE.

ISAAC H. ATHEY, OF CHICAGO, ILLINOIS, ASSIGNOR TO DELMAR J. BURLINGAME, OF LA GRANGE, ILLINOIS.

CABINET.

No. 908,830.

Specification of Letters Patent.

Patented Jan. 5, 1909.

Application filed May 18, 1908. Serial No. 433,393.

To all whom it may concern:

Be it known that I, ISAAC H. ATHEY, a citizen of the United States, residing at Chicago, in the county of Cook and State of Illinois, have invented a new and useful Improvement in Cabinets, of which the following is a specification.

My invention relates more particularly to improvements in cabinets of the variety suitable for the reception of papers, drawings and other articles of a like nature of comparatively large dimensions.

My primary object is to provide a compact construction of cabinet suitable for the purpose above specified which will be adapted to receive and support therein, in vertical condition, pockets or other suitable receptacles for receiving papers, drawings or the like and be capable of extension for rendering the interior of the cabinet readily accessible for easy removal of the pockets; and another important object is to provide a construction whereby a portion thereof may be caused to be moved into a position for affording a rest for the pockets and their contents after their removal from the cabinet.

My invention is illustrated in the accompanying drawings, in which—

Figure 1 is a view in sectional elevation, the section being taken at the line 1 on Fig. 4 and viewed in the direction of the arrow, this view showing the cabinet in closed condition. Fig. 2 is a view similar to that of Fig. 1 showing the cabinet in open position with a removable pocket for papers, drawings or the like located in the cabinet. Fig. 3 is a view similar to Fig. 1 showing the cabinet open and the rest or shelf of the cabinet in extended position for use. Fig. 4 is an enlarged broken section taken at the line 4 on Fig. 1 and viewed in the direction of the arrow. Fig. 5 is an enlarged section taken at the line 5 on Fig. 1 and viewed in the direction of the arrow; and Fig. 6 is an enlarged broken section taken at the line 6 on Fig. 4 and viewed in the direction of the arrow.

The cabinet illustrated in the drawings is of the vertical type comprising a back 7, a bottom 8, sides 9, a front panel 10 and a swinging top 11.

The pockets in which the drawings or papers to be stored in the cabinet are placed may be supported in the cabinet in any suitable way, and the pockets may be of any

suitable style. In the construction shown, 55 the inner opposed surfaces of the sides 9 carry cleats 12 near the top of the cabinet, these cleats extending horizontally and affording ledges upon which the transverse supporting bars 13 of the pockets rest at 60 their ends, the receptacle-portions 14 of the pockets depending as represented in Fig. 2. The cleats 12 and the bottom 8 extend short of the front vertical edges of the sides 9, and hinged to the forward edge of the bottom 8, 65 as indicated at 15, is an inverted U-shaped frame 16 extending a very short distance above the top edges of the cleats 12 and formed of two upright strips 17 united together at their upper ends by a cross-piece 70 18, the upper opposite corner-portions of which are recessed, as indicated at 19, to permit the frame 16 to be swung inwardly beyond the outer ends of the cleats 12. The panel 10 is hinged to the cross-piece 18 near 75 its opposite ends, as indicated at 20, to extend flush at its upper edge with the top edges of the sides 9 and fit against the forward edge-portion of the bottom 8 of the cabinet when the cabinet is closed as represented in Fig. 1.

The cross-bar 18 has pivoted to it near its opposite ends, as indicated at 21, metal strips 22, each provided with an elongated slot 23 through which a screw 24 in the vertical face of each cleat 12 passes, the strips 22 being so disposed as to cause them to be constantly held in flatwise relation against the cleats 12. Similar strips 25 are pivoted as indicated at 26 to the opposite sides of the 90 panel 10 near its top to lie flatwise against the adjacent inner surfaces of the sides 9 above the cleats 12 and be held in such position against disengagement from the sides 9 during the operation of the device, by screws 95 27 fastened in the sides 9 and passing through the slots 28 on the strips 25. The panel 10 has connected to it, a slight distance above its lowermost edge and intermediate its vertical marginal edges, as by a spring- 100 hinge 29, a leg 30, which is formed with a reduced upper end-portion 31 which extends into a recess 32 provided in the cross-bar 18, when the parts are in the position illustrated in Figs. 1 and 2. The top 11 of the cabinet 105 is constructed with a depending flange 33, which, when the parts of the device are in the position illustrated in Fig. 1, fits over the

upper marginal edge of the panel 10 and holds in position the swinging parts hereinbefore referred to.

Assuming the cabinet to be closed and containing pockets introduced therein as described of the one illustrated in Fig. 2, the operation of the device is as follows: The cover 11 is first raised, thereby withdrawing the flange 33 from engagement with the 10 panel or front 10. The panel may then be grasped at its upper edge and pulled outward toward the operator, thereby causing the frame 16 to turn at its hinge-connection 15 with the bottom 8, the frame 16 swinging out 15 at its upper end - portion to the position illustrated in Fig. 2 in which the metal strips 22 and 25 arrest further swinging of the member 16 by engagement of the ends of their slots with the screws, the metal strips 20 in this position of the swinging parts of the cabinet being extended to the limit of their outward movement. It will be noted that the panel or front 10 depends at its hinge-connection with the frame 16, and that the 25 leg 30 is held in folded position and completely out of the way. With the frame 16 and panel 10 swung out as illustrated the pockets may be readily moved apart to separate them from their previously packed condition, by causing them to be distributed 30 along the top surfaces of the cleats 12 and the upper edges of the strips 22, the strips 25 serving to maintain the alinement of the supporting bars 13 at their opposite ends, so 35 that when the case is closed the bars 13 will be accurately guided into position between the sides of the cabinet.

It is often desirable that the contents of the pocket or pockets removed from the 40 cabinet for inspection be examined at the cabinet, and as the drawings or papers are liable to be of a bulky nature and of large dimensions, a proper place to inspect them is not ordinarily accessible. To make the 45 cabinet convenient for this purpose as well as for a storing receptacle, I have provided the panel 10, which not only forms the front of the cabinet when the latter is closed, but serves as a table or ledge of the desirable 50 dimensions for inspecting the contents of the pocket or pockets when the panel is swung to the position indicated in Fig. 3, in which position it is held by the leg 30, which in the swinging of the panel 10 to the position referred to becomes disengaged from the cross-piece 18, and under the action of its spring-hinge 29 turns to a position for supporting 55 the panel 10 in the position in which it serves as a shelf.

60 The operation of closing the cabinet is manifest. Generally speaking, the leg 30 is swung upon its hinge to lie against the panel 10, the latter is then lowered to the position illustrated in Fig. 2 and the member 16 65 swung upon its connections 15 with the bot-

tom 8 to position these swinging parts as illustrated in Fig. 1. The top is then lowered to lock these swinging parts in folded position. As a means for holding the panel 10 in position at its lower edge-portion, I 70 provide in the inner faces of the sides 9 near their forward vertical edges, spring-pressed plungers 34 which fit into registering sockets 36 in the lateral vertical edges of the panel 10, the operation of these plungers being well 75 understood in the art.

By constructing a cabinet in accordance with my invention, it may be filled to its capacity and still render the removal from it of one or more of its pockets an easy operation without danger of mutilating the pockets or their contents. 80

Another decided advantage offered by this construction is that even though the cabinet is packed to its utmost capacity with the 85 pockets, when the front is swung out, as before described, the pockets may be separated from each other by sliding them along the upper portions of the cleats 12 and the strips 22, and thus the selection of the pocket 90 desired to be removed may be readily and easily accomplished.

The provision of the panel 10 serves to afford a very convenient rest for the pockets after their removal from the cabinet, and 95 thus the time consumed in referring to the contents of the cabinet is reduced to the minimum.

What I claim as new, and desire to secure by Letters Patent, is— 100

1. In a cabinet, the combination with its casing having a movable vertical section pivoted near its lower end to the cabinet and adapted to be swung outwardly at its upper end, of means for supporting pockets, or the like, in depending position in the casing, and extension-supports near the opposite sides of said pivoted section slidingly confined at the sides of the cabinet substantially in line with said supporting means, for the purpose set 110 forth.

2. In a cabinet, the combination with its casing having a movable vertical section mounted to permit it to be swung outwardly at its upper end, ledges provided adjacent to the sides of the cabinet for supporting pockets, or the like, in depending position in the casing, and extension-supports in the form of metal strips connected near their outer ends to the movable section of the casing and supported at their inner ends to adapt them to extend at their upper edges in substantial alinement with said ledges, for the purpose set forth. 115

3. In a cabinet, the combination with its casing having a vertical front section supported in a manner to permit it to be moved bodily in a direction away from the casing and to be swung to a position in which it affords a shelf, means for supporting pockets, 125 130

or the like, in depending position in the casing in a manner to permit them to be lifted bodily out of the top of the cabinet, and extension supporting means constructed and arranged to be moved into extended position when the front section is moved out from the casing.

4. In a cabinet, the combination with its casing having a vertical section, means for supporting pockets, or the like, in depending position in the casing, and a second swinging section forming the front-side of the casing pivoted near its upper end to said first-named section to adapt it to be swung to a position in which it affords a shelf for the pockets removed from the casing.

5. In a cabinet, the combination with its casing having a vertical section pivoted near its lower end to adapt it to be swung outwardly at its upper end, of means for supporting pockets, or the like, in depending position in the casing, means for affording an extension-support for the pockets when the movable section is swung outwardly, a second swinging section pivoted near its upper end to said first-named movable section to adapt it to be swung to a position in which it affords a shelf for the pockets removed from the casing, and means for supporting said second swinging section in raised position.

6. In a cabinet, the combination with its casing having a section forming the front thereof, and a frame pivoted at its lower end to the bottom of the casing and to which frame-member the front is pivoted near its upper end-portion, of means for supporting pockets, or the like, in depending position in the cabinet, and extension means connected with said frame-member and coöperating with said first-named means, for the purpose set forth.

7. A cabinet comprising in combination a back, bottom and sides joined together, a frame pivoted near its lower end to the forward edge of the bottom of the casing, a front for the casing pivoted near its upper end to the upper end of the frame, a swinging cover, means for supporting pockets, or the like, in depending position in the casing, and means forming an extension-support for the pockets when the frame is swung outwardly at its upper end.

8. In a cabinet, the combination with its casing having a vertical section pivoted near its lower end to adapt it to be swung outwardly at its upper end, of means for supporting pockets, or the like, in depending position in the casing, extension-supports connected with said swinging section and coöperating with said first-named means, and means movable with the swinging section and extending beyond the ends of the pockets for maintaining the alinement of the latter, for the purpose set forth.

9. In a cabinet, the combination with its casing having a movable vertical section pivoted near its lower end to the cabinet, of ledges, or the like, at the sides of the casing adapted to dependently support pockets, or the like, at their opposite ends in the casing, and means coöperating with said ledges, or the like, and connected with said movable section for forming an extension to said pocket-supporting means and substantially in alinement therewith and adapted to be moved into operative position when the vertical section is swung outwardly at its top, for the purpose set forth.

ISAAC H. ATHEY.
